UNITED STATES PATENT OFFICE.

HENRY NEUMAN, OF ANDERSON, INDIANA.

GEARING.

1,097,460.

Specification of Letters Patent.

Patented May 19, 1914.

Application filed October 29, 1913. Serial No. 798,111.

To all whom it may concern:

Be it known that I, HENRY NEUMAN, a citizen of the United States, residing at Anderson, in the county of Madison and State 5 of Indiana, have invented new and useful Improvements in Gearing, of which the following is a specification.

The present invention relates to operating mechanism chiefly for washing machines but 10 it is obvious that such mechanism may be readily adapted to machines of analogous nature.

The invention provides a reciprocating rack, a fly wheel having connection with 15 such rack and connecting means between the rack and the part to be driven, the fly wheel being driven continuously in the same direction whereas the rack bar has a reciprocating movement imparted thereto and in 20 turn actuates the driven part by means of an oscillatory movement.

The invention consists of the novel features, details of construction and combination of parts, which hereinafter will be more 25 particularly set forth, illustrated in the accompanying drawings, and pointed out in the appended claims.

Referring to the drawings, forming a part of the specification, Figure 1 is a side 30 view of an operating mechanism embodying the invention showing the same in connection with a washing machine. Fig. 2 is a section on the line $x-x$ of Fig. 1. Fig. 3 is a horizontal section on the line $y-y$ of 35 Fig. 1. Fig. 4 is a detail view of the rack. Fig. 5 is a detail view of a modification in which a rotary movement is imparted directly to the fly wheel and the latter in turn imparting a reciprocating movement to the 40 rack.

Corresponding and like parts are referred to in the following description, and indicated in all of the views of the drawings, by the same reference characters.

45 The numeral 1 designates a tub which is adapted to receive the mechanism such as the rubber or other agitator when the mechanism is adapted for operating the washing machine. A vertical shaft 2 passes centrally 50 through the bottom of the tub and is provided at its lower end with a mutilated pinion 3 which is arranged to coöperate with a rack 4 having a toothed portion 5 arranged to mesh with the teeth of the pinion 55 3. A plate 6 is secured to the bottom of the tub and is formed with a plurality of

lugs 7 of hook form which engage and support the rack 4 and direct such rack in its reciprocating movements. Upon imparting a reciprocating movement to the rack 4 the 60 pinion 3 is oscillated and such movement is transmitted by means of the shaft 2 to the part to be operated. For imparting a reciprocating movement to the rack 4 a lever 8 is located at one side of the tub and is 65 pivoted to a bracket 9. A link 10 connects the lower end of the lever 8 with the rack 4. A roller 11 is arranged to engage an edge of the rack 4 and materially lessens the friction incident to the operation of such rack. 70

A fly wheel 12 is located below the tub 1 and in a plane parallel with the bottom thereof. The fly wheel is operated by means of a bearing 13 which is connected by arms 14 with the legs 15 upon which the tub is 75 mounted. The fly wheel 12 is provided with a wrist pin 16 which is adapted to engage a slotted portion 17 depending from the rack 4, the slotted portion 17 extending transversely at an angle of about 6° so as to prevent the wrist pin from stopping on a dead center. The parts are so proportioned and arranged that a reciprocating movement of the rack imparts a continuous rotary movement to the fly wheel and an oscillatory 80 movement to the pinion 3 and part to be driven.

In the modification shown in the Fig. 5 the lever 8 and link 10 are dispensed with and the fly wheel 12 has a shaft which extends through the bearing 13 and is provided at its lower end with a beveled gear 17' which is in mesh with a beveled gear 18 secured to the inner end of a horizontal shaft 19 mounted in suitable bearings and 95 provided at its outer end with a pulley 20 to which power is applied in any manner by means of a drive belt. In this construction the power is applied to the fly wheel and the latter by reason of its connection 100 with the rack imparts a reciprocating movement thereto.

From the foregoing description taken in connection with the accompanying drawings, the advantages of the construction and 105 of the method of operation will be readily apparent to those skilled in the art to which the invention appertains, and while I have described the principle of operation of the invention, together with the device which I 110 now consider to be the best embodiment thereto, I desire to have it understood that

the device shown is merely illustrative, and that such changes may be made when desired as are within the scope of the claims appended hereto.

5 Having thus described the invention what is claimed as new, is:—

1. In operating mechanism of the character specified the combination of a rack having a toothed portion and a transverse slotted portion, a pinion having its teeth in mesh with the toothed portion of the rack and adapted to receive an oscillatory movement and a fly wheel having a wrist pin in engagement with the transversely slotted portion of the rack, the parts being arranged to admit of the fly wheel receiving a continuous rotary movement and the pinion an oscillatory movement.

2. In operating mechanism of the character specified, the combination of a rack having a toothed portion and a transverse slotted portion, the slot extending at an

angle at approximately 6° , a pinion having its teeth in mesh with the toothed portion of the rack and a fly wheel having a wrist pin entering the transversely slotted portion of the rack.

3. In operating mechanism of the character specified the combination of a plate formed with hook shaped lugs, a rack mounted in such lugs and adapted to have a reciprocating movement imparted thereto, said rack having a toothed portion and a transversely slotted portion, a pinion having its teeth in mesh with the toothed portions of the rack and a fly wheel having a wrist pin arranged to operate in the transversely slotted portions of the rack.

In testimony whereof I affix my signature in presence of two witnesses.

HENRY NEUMAN.
